United States Patent Office

Des. 189,387
Patented Nov. 29, 1960

189,387

BOAT

George C. Rorie, Dallas, Tex., assignor to Lone Star
Boat Company, Grand Prairie, Tex., a corporation of Texas

Filed May 11, 1959, Ser. No. 55,867

Term of patent 14 years

(Cl. D71—1)

Fig. I

Fig. II

Fig. I is a top plan view of a boat showing my new design; and

Fig. II is a perspective view thereof.

The dominant feature of my design resides in the recessed step shown in full lines.

I claim:

The ornamental design for a boat, as shown and described.
